Fig. 3

Fig. 4

FIG. 1 is a perspective view of a combined motor shroud and blade housing for a lawn mower embodying my new design;

FIG. 2 is an enlarged top plan view thereof;

FIG. 3 is an elevation as seen from the right of FIG. 2;

FIG. 4 is an elevation as seen from the front of FIG. 2;

FIG. 5 is an elevation as seen from the left of FIG. 2; and

FIG. 6 is an elevation as seen from the rear of FIG. 2. The dominant features of my design reside in the portions shown in full lines.

I claim:

The ornamental design for a combined motor shroud and blade housing for a lawn mower, substantially as shown and described.
